Des. 195,631

Patented July 9, 1963

195,631

INDOOR HORSESHOE GAME TARGET

Harold Warren Klingaman, 780 17th St., Primghar, Iowa

Filed Nov. 20, 1962, Ser. No. 72,551

Term of patent 3½ years

(Cl. D34—5)

FIG. 1

FIG. 2

Des. 195,631

PAGE 2

Fig. 3

FIG. 1 is a front perspective view of an indoor horseshoe game target, showing my new design;

FIG. 2 is a reduced rear elevational view of the indoor horseshoe game target;

FIG. 3 is an enlarged top plan view of the indoor horseshoe game target;

FIG. 4 is a side elevational view of the indoor horseshoe game target looking toward the left in FIG. 3, with the opposite side being identical thereto; and

FIG. 5 is a reduced rear perspective view of my new design.

I claim:

The ornamental design for an indoor horseshoe game target, substantially as shown.
